UNITED STATES PATENT OFFICE.

OLIVER E. WALKER, OF CINCINNATI, OHIO, ASSIGNOR TO HIMSELF AND
CHARLES F. STITES, OF SAME PLACE.

IMPROVEMENT IN CANS FOR PAINT, &c.

Specification forming part of Letters Patent No. **142,971**, dated September 16, 1873; application filed
June 7, 1873.

To all whom it may concern:

Be it known that I, OLIVER E. WALKER, of Cincinnati, in the county of Hamilton and State of Ohio, have invented a new and Improved Paint-Can, of which the following is a specification:

My invention consists of a paint-can composed of a metal cylinder with wooden heads at each end, secured, by a flange of the cylinder end turned over the outside and a bead raised on the inside of the cylinder against the inside of the head, by impressing a groove in the outside of the cylinder, and one of the heads with a large opening through it to allow of putting in and removing the paint, and a plug or bung is used to close the hole.

The drawing is a sectional elevation of my improved paint-can.

A is the metal cylinder, and B and C the heads, of wood. These heads are secured by a bead, *a*, and flange *b* milled down at the

sides of their edges after they are fitted in the cylinder; or, if preferred, the bead may be formed beforehand. D is the opening in one of the heads, and E the plug or bung for closing it.

By this arrangement I make a cheaper and also a more durable can than can be made of sheet metal, wholly.

Having thus described my invention, I claim as new and desire to secure by Letters Patent—

A combined paint-bucket and packing-can, consisting of a metallic bailed cylinder, A, the non-removable wooden heads B C, and the plug D, constructed and put together substantially in the manner described.

OLIVER E. WALKER.
